I. BENJAMINS

WRITING PEN

Filed June 10, 1926

Inventor:

Israel Benjamins.

UNITED STATES PATENT OFFICE.

ISRAEL BENJAMINS, OF BROOKLYN, NEW YORK.

WRITING PEN.

Application filed June 10, 1926. Serial No. 115,040.

My invention relates to improvements in writing pens which are removable in penholders and are commonly called pen points and it consists in the novel features herein-
5 after more fully described.

One of the objects of my improvement is—
to produce a writing pen, which may be
dipped into the ink comparatively infre-
quently.

10 Another object of my improvement is to
have a supply of ink stored up in conjunc-
tion with a pen to be yielded gradually to
the point of the pen.

15 A further object of my improvement is—
to transform any standard pen into my im-
proved writing pen by attaching thereto cer-
tain inexpensive and simple parts; to have a
supply of ink stored therewith, to be yielded
gradually to the point of the pen.

20 Other objects and advantages will herein-
after appear.

I attain these objects by the writing pen,
two forms of which are illustrated in the
accompanying drawings, or by any mechani-
cal equivalent or obvious modification of the
25 same.

In the drawings Fig. 1 is a section on the
line 1—1 of Fig. 2; Fig. 2 is a top view or
plan of one form of my improved writing
30 pen.

Fig. 3 is a side elevation of another form
of my writing pen, and Fig. 4 is a section on
the line 4—4 of Fig. 3 looking from left to
right in Fig. 3.

35 Similar numerals refer to similar parts
throughout the several views.

In the form of my writing pen, shown in
Figs. 1 and 2, 11 designates the main body of
a standard pen, which has therein a slot 13
40 and a slit 14 extending therefrom to the
point of the pen.

A bracket or carrier 12 may be soldered
or welded to the underside of the pen 11, to
45 support therebetween a pad or mass of ab-
sorbent material 15, which may consist of a
lump of cotton, a piece of sponge or a strip
or strips of felt, cloth or any other suitable
material.

The carrier 12 is shown in Fig. 1 as having
50 at the forward end thereof a small opening
12^a for the forward part of the pad 15 to
extend therethrough; the rear end 12^b of the
carrier 12 is open, to allow the pad 15 to be
inserted therethrough.

The pad 15 is shown in Fig. 1 as being 55
held in contact with the underside of the
main body 11 of the pen near the point
thereof.

In the form of my writing pen, shown in
Figs. 3 and 4, a bracket or carrier 22 is se-
cured to the body 21 of a standard pen, hav-
ing therein a slot 23 and a slit 24 extending
therefrom to the point of the pen, by means
of two lateral extensions or wings 25, which
extend from the sides of the carrier 22 and 65
are bent over and interlocked with the edges
of the pen 21, as shown in Fig. 4.

A pad or mass of absorbent material 26
is supported by said carrier 22 therebetween
and said pen 21 in contact with the under-
70 side of the pen 21, and it may extend through
the opening 22^a at the forward end of the
bracket 22; the rear end 22^b of the bracket
22 is open as in the modification shown in
Fig. 1, and it serves the same purpose. 75

It is evident that, when the forward end
of my improved writing pen is dipped into
an inkwell, a supply of ink will be absorbed
by the pad or mass of absorbent material,
which ink will gradually be yielded to the 80
underside of the pen and flow along the slit
of the pen to the point thereof.

In this way any standard pen may be
converted into my improved writing pen, as
shown in Figs. 1 to 4 inclusive. 85

The best proportions of my improved
writing pen may be determined by experi-
ment, and the shape of sundry parts thereof
may be varied a great deal.

Many other changes may be made in the 90
form of my improved writing pen and the
design of the details thereof without depart-
ing from the main scope of my invention, and
parts of my invention may be used without
other parts, if desired. 95

I do not, therefore, restrict myself to the
details as shown in the drawings, but I in-
tend to include also all mechanical equiva-
lents and obvious modifications of the same
within the scope of my invention. 100

I claim as my invention and desire to se-
cure by Letters Patent:

1. As an article of manufacture a remov-
able pen point, comprising a main body, a
105 bracket, secured thereto in a way to form
an integral structure therewith, and absorb-
ent material, supported by said bracket in
contact with the underside of said pen point

near the forward end thereof, said bracket and said pen point having therebetween an opening at the forward end thereof, to allow said material to absorb ink therethrough when said end is dipped into an inkwell.

2. As an article of manufacture a removable pen point, comprising a main body, a

bracket, secured thereto in a way to form an integral structure therewith, and absorbent material supported by said bracket in contact with the underside of said body near the forward end thereof.

Executed on the 9th day of June, 1926.

ISRAEL BENJAMINS.
